UNITED STATES PATENT OFFICE.

ANTOINE SIGALON, OF LYON, FRANCE, ASSIGNOR TO ARMAND CARRETTE, OF PARIS,
FRANCE.

SCREW-CUTTING DEVICE.

1,373,104.

Specification of Letters Patent.

Patented Mar. 29, 1921.

Application filed December 7, 1918. Serial No. 265,770.

To all whom it may concern:

Be it known that I, ANTOINE SIGALON, a citizen of the Republic of France, residing at Lyon, Rhône, 28 Rue Bancel, in the Republic of France, engineer, have invented certain new and useful Improvements in Screw-Cutting Devices, of which the following is a specification.

This invention has for its object to provide an improved screw-cutting device for cutting screw threads of different diameters, between very wide diametral limits, by means of one and the same set of dies having a given pitch, the dies that are employed being easily removable and replaceable by other dies having a different pitch.

By way of example, Figure 1 of the accompanying drawings illustrates an improved hand-actuated screw-cutting device according to this invention.

Fig. 2 is a cross section thereof on the line 2—2 of Fig. 1.

Figs. 3, 4 and 5 are detail views of the chief parts of this improved screw-cutting device.

Fig. 6 is a longitudinal section, and Fig. 7 is a section on the line 7—7 of Fig. 6, of a power-driven screw-cutting device for a lathe.

Fig. 8 and Fig. 9 are views showing the different positions of the hooks and lever.

The improved manual screw-cutting device, in the form shown in Figs. 1 to 5, consists of a circular box or casing *a* having formed in one piece therewith two radially extending handles *b* for operating the same. In the internal cavity of this box *a* are arranged four similar dies *c* one of which is shown in detail in front and side view in Fig. 5. Each of these dies consists of a body part terminating at one end in a cylindrical head *c*¹ serrated at its other end for forming a screw thread of any desired pitch. On one side of the body part of the die is a stud *c*². The dies have their cylindrical heads *c*¹ seated in bearings *d*, provided in the interior of the box *a*, in which they are capable of rocking. The box is closed on two sides by plates *e* and *g* bored concentrically to receive a screw-blank of the maximum diameter for which the screw-cutting device is made. The plate *e* is seated in the margin of said box so as to be freely rotatable therein on its own axis. This plate *g* is held in place by a ring *f*. The plate *e* closes the lower side of the box, and has two stems *h* that extend through the plate *e*. Two milled nuts *i* are screwed on these stems and serve to hold the plate *g* in place but allow of its easy removal. The plate *e* has four tangential slots *j* in which the studs *c*² of the dies extend, and by the rotation of the plate *e* on its own axis, the dies are caused to move their serrated ends toward or away from one another. This adjustment of the dies in the bearings *d* of the box, enables a screw-thread to be cut of any size within predetermined limits. The rotation of the plate *e* and the fixing of the said plate for the purpose of maintaining the dies at a given adjustment, are effected by the following means:—

In the said plate *e* and disposed axially at right angles thereto there is fixed a screw *k*. At another point against the exterior surface of the box *a* there is provided a bracket *l* in which is rotatably mounted a stud *m* ending in a head that is apertured and internally threaded to a nut for a screw *n*, this screw being actuated by means of a milled head *n*¹. This screw *n* is terminated at its other end by a hook *n*² which is adapted to engage the screw *k* of the plate *e*. On the contrary when the lever *q* is brought into the position shown in Fig. 9, the stud *c* will drive back the hook *n*² and the latter will therefore set free the screw *k*, whereby the screw *n* can be pivoted upon its support *l*. The comb-shaped members can then be instantly separated to disengage the draw-plate.

The diameter to which each adjustment of the dies corresponds may be indicated on a scale (not shown) carried by the ring *f*, and pointer or a micrometer index may be engraved on the plate *e* and serve as a register mark for indicating the divisions of the seals.

By removing the plate *g* it is easy to withdraw the dies either for cleaning purposes or for substituting therefor other dies of a different pitch.

For its application to lathes the improved screw cutting device may be modified in the manner shown in Figs. 6 and 7. According to this construction, the body part *a*¹ of the screw-cutting device ends in a tail or sleeve *a*² held by the lathe. In front of this body part there is provided an annulus *r* that contains bearings wherein the dies *c* are piv-

oted. The rotation of this annulus causes the dies to swing outward, the studs c^2 of these latter being engaged in slots j^1 formed in the body part a^1 . The annulus r is fixed 5 to a sleeve s that surrounds the body part a^1 and is held by spurs t engaging in slots u that allow the sleeve s to rotate. The adjustment of the dies to the diameter of the screw thread to be cut, is effected, as in 10 the hand actuated screw-cutting device, by means of a screw n threaded in a pivotally mounted nut carried by the body part a^1 . The screw n has a hook n^2 , which engages 15 with a screw k^1 carried by the sleeve s . The disengagement of the hook is effected by 20 the rotation of the spur o^1 the movement of which can be easily produced automatically by an adjustable rod v being caused to abut against a stop that rotates with the spindle 25 of the lathe and is adjusted to open the screw-cutting device after a determined traverse.

The removal of the dies is effected by 25 withdrawing a plate g^1 that is held by nuts i^1 screwed on the bolts h^1 .

Having now particularly described the construction and operation of my said invention, I declare that what I claim is:—

1. A screw-cutting device comprising 30 screw-cutting dies, a casing formed in its internal periphery with bearings for the

screw-cutting dies, each die having its outer end pivoted in one of said bearings and being provided on one side with a stud, an annular disk mounted rotatably on the said casing and being formed with slots wherein the said studs of the dies are slidably engaged, and means including a screw and a nut for maintaining the said disk in different adjustments relative to the said casing, 35 the said screw having a head on one end and a hook on its opposite end, the said disk being provided with a projection adapted to be engaged by said hook of the said screw. 40

2. In a screw-cutting device the combination 45 of a casing, an annular disk mounted rotatably on the said casing and formed with slots, screw-cutting dies pivoted in the said casing, each of said dies being formed with a stud, these studs being respectively 50 engaged in said slots, a projection on the said disk, a nut mounted rotatably on the said casing, a screw in the said nut, one end of the said screw constituting a hook for engaging the said projection, and a pivoted 55 lever adapted to push the said hooked end of the said screw away from the said projection.

ANTOINE SIGALON.
